UNITED STATES PATENT OFFICE.

HOWARD M. WEBSTER, OF CHICAGO, ILLINOIS, ASSIGNEE TO THE YODEE-MORRIS COMPANY, OF CLEVELAND, OHIO, A CORPORATION OF OHIO.

LIQUID-FUEL BURNER.

Application filed October 2, 1922. Serial No. 591,684.

This invention relates to liquid fuel burners and its object is to obtain more perfect combustion and greater efficiency than has been customary with burners of this class 5 now in general use by providing means of comparatively simple construction for first vaporizing the fuel mechanically and then gasifying it by introducing air and applying heat whereby a highly combustible mixture 10 is obtained which will burn with the highest efficiency and without carbonizing the burner.

Another object of the invention is to provide means for finely dividing the liquid 15 fuel supply by centrifugal action and thereby putting it into a most favorable condition for gasifying at the burner.

And further objects of the invention are 20 to provide means for properly feeding the liquid fuel to the burner; for cooling the operating motor; for preventing heat at the burner from affecting the motor or traveling down to the supply tank; for distributing the liquid fuel centrifugally and supplying 25 air within the burner from below and from above for vaporizing or gasifying the fuel and promoting combustion; for distributing the gasified fuel through the burner in a finely divided form to promote combustion; 30 and to return condensed fuel from within the burner to the supply tank.

In the accompanying drawings I have 35 illustrated a selected embodiment of the invention which I have tested satisfactorily and referring thereto—

Fig. 1 is a central sectional view.

Fig. 2 is a horizontal sectional view of the burner on the line 2—2 of Fig. 1.

Fig. 2' illustrates another form of slit.

40 Fig. 3 is a horizontal sectional view on the line 3—3 of Fig. 1.

Fig. 4 is a horizontal sectional view on the line 4—4 of Fig. 1.

Fig. 5 is a vertical sectional view on the line 5—5 of Fig. 4.

Figs. 6 and 7 are horizontal sectional views on the lines 6—6 and 7—7 respectively of Fig. 1.

50 Fig. 8 is a bottom plan view of the centrifugal pump casing.

Referring to the drawings 10 is an electric motor which is mounted upon a suitable support 11 on the top of a supply tank 12, and this motor operates the vertical shaft 13 55 forming its rotor which projects into the

stuffing box 14, a chamber 15 and a stuffing box 16 and carries a centrifugal pump 17 in a pump cylinder 18 having an opening 19 in its bottom. This opening is located adjacent the bottom of the supply tank so that the pump cylinder may be kept supplied with liquid fuel from the supply in the tank 12; and this supply is maintained at a predetermined level by a float valve 20 (Fig. 5) within the tank and controlling the inlet of liquid fuel through the pipe 21 from a storage tank. A passage 22 connects the pump cylinder with the chamber 15 and a valve 23 is arranged to be adjusted to control the flow of the liquid fuel from the pump cylinder 70 through the passage. This control valve is secured in adjusted position by a lock screw 24.

The shaft 13 has a hollow portion 25 near its lower end and a plurality of ports 26 75 form a communication between the chamber 15 and said hollow portion which is connected by a longitudinal passage 27 with the hollow portion 28 at the upper end of the shaft. The pump forces oil through the hollow shaft. A plug 29 is located within the hollow portion at the upper end of the shaft and above the lower end of said hollow portion. The lower end of the plug is provided with a plurality of longitudinal grooves 30 80 which communicate with lateral ports 31 leading to the spaces 32 between the disks 33 of a centrifugal distributor 34.

A burner head 35 encloses the distributor 34 and is supported from the tank 12 which forms the base of the apparatus. This burner head consists of a short cylinder having a plurality of angularly disposed slits 35' therein (Fig. 2). A pilot light comprising a tubular ring 36 is supported beneath the head at the outer edge thereof by the lugs, and this ring receives liquid fuel or gas from a suitable source through the pipe 36'. A drain pipe 38 is connected with an angular depression 39 in the head and with the top of the tank at 38' to deliver back into the tank any unconsumed fuel that collects in the head.

A fan 40 is carried by the shaft 13 between the motor and the supply tank to keep the motor cool. A cooling member in the form of a hollow dome or water jacket 41 is supported from the supply tank between the head and the motor and is supplied with cold water through the pipe 42 and has an outlet 105 110

43. This cooling member prevents the heat of the burner from being communicated to the motor and keeps the motor cool.

A fan 44 is mounted on the shaft 13 between the motor and the head preferably within a downward contracted extension 45 of the burner head which provides an air passage 45' leading into the head at the bottom of the distributor. A tapered collar 46 is adjustably mounted on the shaft 13 above the fan 44 and within the extension 45 to control the air inlet to the head from the fan 44.

A similar fan 47 is mounted on the shaft 13 within the upper contracted extension 48 of the burner head which is connected with an air inlet 48'. A tapered collar 49 is adjustably mounted on the shaft 13 below the fan 47 to control the air inlet to the head from the fan 47.

The above described arrangement makes possible an exceedingly compact and efficient burner. The hollow shaft is used not only as a pipe to convey oil from a source of supply to the burner head but it is used to develop the power which forces oil through itself. This function is made possible by the fact that the hollow shaft forms the rotor of the motor and therefore may be used to operate the pump which forces oil through the shaft. The shaft is further employed to operate other parts of the mechanism, such as, the centrifugal distributor and the fans.

35. My invention provides an apparatus of simple construction which can be manufactured and installed at comparatively low cost and which is adapted to feed the fuel in sufficient quantities to the distributor and there to distribute the fuel by centrifugal action to the outside of the head where it is ignited from the pilot light and burns under substantially perfect combustion. One of the especially important features of 40 the invention is the centrifugal distributor whereby the liquid fuel is first divided into a comparatively thin film between the spaced discs or plates and is thrown out by these discs or plates centrifugally and at the same 45 time is thoroughly mixed with the air flowing in at the bottom and at the top of the head as induced by fans 44 and 47. The result of the centrifugal treatment of the liquid fuel is to finely sub-divide it so that it will very easily mix with the inflowing air and so will become thoroughly mixed with air inside the head and will be discharged through the slits 35' of the burner head and ignited outside the head. These slits are 50 rearwardly inclined in the direction of revolution of the distributor so that the gasified fuel will be discharged against the burner wall and find its way through the slits and not be thrown directly through the slits 55 which might happen if the slits are radially

disposed. Instead of providing a plurality of vertically disposed slits 35' I may provide the burner with one or more inclined peripheral slits as shown at 35" in Fig. 2a.

My theory of the action which takes place in vaporizing and gasifying the liquid fuel in the burner is substantially as follows:— The distributor first divides the liquid fuel into a plurality of thin films and then discharges it under considerable pressure laterally in the head and against the outer wall thereof. The outer wall of the head is heated by the pilot light and, of course, becomes more highly heated when the burner is actively working. This vaporized fuel is finely divided in the head and mixed with the inflowing air from the fans 44 and 47. In other words, the combined action of the centrifugal distributor, and the inflowing currents of air in the presence of heat, vaporizes and gasifies the fuel within the confines of the head so that it issues through the slits thereof in the form of a highly volatile gas and is then ignited, outside the head. I prefer to provide inclined slits in the head for the passage of the gas because I find it produces what I consider to be a more satisfactory flame for heating purposes and I also believe that the retardation of the flow by reason of the narrowness and inclination of the slits tends to promote the gasifying action. The head being substantially closed permits thorough mixing of the air and fuel before it becomes ignited.

I have found in practice that kerosene and fuel oil can be used in my apparatus satisfactorily, that the apparatus will work without objectionable odor and practically free from carbonization. Tests of the apparatus have demonstrated that a high degree of heat can be quickly produced with a consumption of very little fuel and that the use of the apparatus will be economical. The apparatus can be used in domestic furnaces of all kinds and in factory and other heating plants and I contemplate building the burner in sizes suitable for different purposes.

A drain from the head to the tank is provided to permit the escape of any ungassified liquid fuel, or any condensation thereof; this is a safety precaution to permit the escape of fuel in case the pilot light is extinguished or the fuel is fed too fast. The vertical slits 35 are positioned at an angle to the direction of rotation of the distributor and this prevents the liquid fuel from being thrown out through the slits by the distributor should the fuel not be properly gasified because of a lack of sufficient heat or feeding an excess of fuel.

I have shown my invention as it is embodied in a complete working burner which I have operated many times and thoroughly tested and which has proven to be entirely

satisfactory; but I am aware that changes may be made in the form, construction and arrangement of parts to adapt the burner for various application and for other purposes and I reserve the right to make all such changes as fairly fall within the scope of the following claims.

I claim:

1. In a liquid fuel burner, the combination of a hollow burner head having a wall provided with a plurality of relatively small spaced openings therein, means for heating said wall, means for admitting fuel to the head, means for admitting air to the head, and means within the head for centrifugally distributing the fuel against said wall, said heated wall acting to gasify the fuel distributed against it within the head and said openings permitting the escape of said 20 gassified fuel from the head.

2. In a liquid fuel burner, the combination of a hollow burner head having a wall provided with a plurality of relatively narrow slits spaced apart therein, means for heating said wall, means for admitting fuel to the head, means for admitting air to the head, and means within the head for centrifugally distributing the fuel against said wall, said heated wall acting to gasify the fuel 25 distributed against it within the head and said slits permitting the escape of said gassified fuel from the head.

3. In a liquid fuel burner, the combination of a hollow burner head, means for admitting fuel to the head, means for admitting air to the head, means within the head for centrifugally distributing the fuel, said head comprising a wall disposed in the path of the distributed fuel to form a baffle therefor and said wall having a plurality of relatively small spaced openings therein, and means for heating said wall, said heated wall acting to gasify the fuel distributed against it within the head and 40 said openings permitting the escape of said gassified fuel from the head.

4. In a liquid fuel burner, the combination of a hollow burner head, a centrifugal distributor within the head, means for revolving said distributor, and means for conveying the fuel to the distributor, said burner having a plurality of slits in its wall opposite the distributor and inclined rearwardly in the direction of revolution of the distributor.

5. In a liquid fuel burner, the combination of the hollow burner head, means for admitting fuel to the head, means for admitting air to the head, means within the head for centrifugally distributing the fuel, said head comprising a wall disposed in the path of the distributed fuel to form a baffle therefor and said wall having a plurality of relatively small spaced openings therein, and means located outside of the burner and

below said openings for heating said wall, said heated wall acting to gasify the fuel distributed against it within the head and said openings permitting the escape of said gassified fuel from the head.

6. In a liquid fuel burner, the combination of a substantially closed burner head, means for conveying the fuel to the head, means for centrifugally distributing the fuel in the head, means for introducing air into the burner at the top and at the bottom thereof, and means for controlling the admission of said air.

7. In a liquid fuel burner, the combination of a substantially closed burner head, means for conveying the fuel to the head, means for centrifugally distributing the fuel in the head, a shaft passing through the head, means on the shaft above and below the head for producing a flow of air into the head at the top and at the bottom thereof, and means for revolving the shaft.

8. In a liquid fuel burner, the combination of a burner head having an opening at the top and bottom thereof, a hollow shaft projecting through the burner, a distributor mounted on the shaft within the burners and comprising a plurality of spaced plates, ports forming communication between the spaces between the plates and the hollow shaft, means operated by the shaft for inducing a flow of the fuel thereto to the ports and means on the shaft above and below the burner operated by shaft for inducing the flow of air into the burner.

9. In a liquid fuel burner, the combination of a burner head, a vertical shaft entering the burner head, a distributor on the shaft within the head for centrifugally distributing the fuel, means for conveying the fuel to the distributor, an electric motor on said shaft, and a domed water jacket interposed between the motor and the burner for protecting the former against the heat of the latter.

10. In a liquid fuel burner, the combination of a hollow burner head having a wall provided with a plurality of relatively spaced openings therein, means within the head for centrifugally distributing the fuel against said wall, means for admitting fuel to the head, means for admitting air to the head above and below the centrifugal distributor, and means for heating said wall, said heated wall acting to gasify the fuel distributed against it within the head and said openings permitting the escape of said gassified fuel from the head.

11. In a liquid fuel burner, the combination of a hollow burner head, a centrifugal distributor arranged within the head and comprising a plurality of spaced disks, means for admitting fuel to the spaces between the disks, means for admitting air to the head above and below the distributor.

- said head comprising a wall disposed in the path of the distributed fuel to form a baffle therefor and said wall having a plurality of relatively small spaced openings therein, and
- 5 means outside of the head for heating said wall, said heated wall acting to gasify the fuel distributed against it within the head and said gasified fuel mixing with the air admitted to the head and said mixture escaping through said openings in the head and being ignited by said means for heating the wall.
- 10 12. In a liquid fuel burner, the combination of a hollow burner head, a centrifugal distributor arranged within the head, means for supplying fuel to said distributor, air conduits in the head above and below said distributor for admitting air to the head, means for controlling the supply of air admitted to the head through said conduits, said head having a wall provided with a plurality of relatively small spaced openings, and means for heating said wall, said heated wall acting to gasify the fuel distributed against it within the head and said gasified fuel mixing with the air admitted to the head and said mixture escaping through said openings in the head and being ignited by said means for heating the wall.
- 15 13. In a liquid fuel burner, the combination of a burner head, a centrifugal distributor operating in the head, a supply tank, a pump cylinder in the supply tank, a pump in the pump cylinder, a hollow shaft carrying the distributor and the pump, a passage connecting the pump cylinder and the hollow shaft, an electric motor on the shaft for operating the same, and a fan mounted on the shaft between the motor and the supply tank.
- 20 14. In a liquid fuel burner, the combination of a burner head having openings at its top and bottom, a centrifugal distributor operating in the head, a supply tank, a pump cylinder, a pump in said cylinder, a hollow shaft carrying said distributor and said pump, a passage connecting the pump cylinder and said hollow shaft, means on the shaft above and below the burner head for introducing air thereinto, and an electric motor mounted on the shaft for operating same.
- 25 15. In a liquid fuel burner, the combination of a hollow burner head having a wall provided with a plurality of relatively small spaced openings therein, a fuel tank, a hollow shaft arranged in said head and said
- 30 tank, a motor mounted on said shaft for revolving the same, a centrifugal distributor mounted on said shaft within the head, a pump mounted on the shaft within the tank for inducing a flow of fuel through the shaft to the distributor, means for admitting air to the head above and below the distributor, and means for heating said wall, said heated wall acting to gasify the fuel distributed against it within the head and said gasified fuel mixing with the air admitted to the head and said mixture escaping through said openings in the head and being ignited by said means for heating the wall.
- 35 16. In a liquid fuel burner, the combination of a hollow burner head having a wall provided with a plurality of relatively small spaced openings therein, a fuel tank, a hollow shaft arranged in said head and tank, a centrifugal distributor mounted within the head upon said shaft, a pump on the shaft within the tank for inducing a flow of fuel through the shaft to the distributor, means for admitting air to the head adjacent the distributor, a motor mounted on the shaft for revolving the same, and cooling means interposed about the shaft between the head and the motor.
- 40 17. In a liquid fuel burner, the combination of a hollow burner head, a centrifugal distributor within the head, means for admitting fuel to the distributor, means for admitting air to the head, said head comprising a wall disposed in the path of the distributed fuel and spaced away from and around the distributor to form a baffle for the distributed fuel and said wall having a plurality of relatively small spaced openings therein, and means outside of the head for heating said wall.
- 45 18. In a liquid fuel burner, the combination of a hollow burner head, a centrifugal distributor within the head, means for admitting fuel to the distributor, means for admitting air to the head, said head comprising a wall disposed in the path of the distributed fuel and spaced away from and around the distributor to form a baffle for the distributed fuel and said wall having a plurality of relatively small spaced openings therein and located adjacent the top of the head, and means located outside of the head and adjacent the bottom of said wall for heating said wall.

HOWARD M. WEBSTER.
